UNITED STATES PATENT OFFICE

128,294

DESIGN FOR A DISPLAY UNIT FOR PERFUME, SACHET, OR THE LIKE

William B. Cohen, St. Paul, Minn., assignor to Stuart Products, Inc., St. Paul, Minn., a corporation of Minnesota

Application March 29, 1941, Serial No. 99,994

Term of patent 3½ years

To all whom it may concern:

Be it known that I, William B. Cohen, a citizen of the United States, residing at St. Paul, county of Ramsey, and State of Minnesota, have invented a new, original, and ornamental Design for a Display Unit for Perfume, Sachet, or the like, of which the following is a specification, reference being had to the accompanying drawing, forming part thereof.

for perfume, sachet, or the like, showing my new design.

I claim:

The ornamental design for a display unit for perfume, sachet, or the like, as shown.

WILLIAM B. COHEN.
